AWNNG

James E. Dietz, Dayton, Ohio

Application April 20, 1955, Serial No. 35,594

Term of patent 14 years

(Cl. D21—6)

FIG. 1

FIG. 2.

Fig. 1 is a perspective view of an awning, showing my new design in closed position; and

Fig. 2 is a perspective view thereof in open position.

The broken line showing of a window and casement is for illustrative purposes only.

I claim:

The ornamental design for an awning, as shown and described.
